UNITED STATES PATENT OFFICE.

ALPHONSE F. PIEPER, OF ROCHESTER, NEW YORK.

DESIGN FOR A CUSPIDOR FIXTURE.

Application filed September 20, 1923. Serial No. 7,275. Term of patent 14 years.

To all whom it may concern:

Be it known that I, ALPHONSE F. PIEPER, a citizen of the United States, residing at Rochester, in the county of Monroe and State of New York, have invented a new, original, and ornamental Design for a Cuspidor Fixture, of which the following is a specification, reference being had to the accompanying drawings, forming part thereof.

Fig. 1 is a side elevation of the cuspidor fixture showing my new design and

Fig. 2 is a plan view of the same.

I claim—

The ornamental design for a cuspidor fixture as shown.

ALPHONSE F. PIEPER.
